CONTROL KNOB OR SIMILAR ARTICLE

Charles M. Dole, Jr., Mount Kisco, N.Y., assignor to
Corning Glass Works, Corning, N.Y., a corpora-
tion of New York

Filed Feb. 23, 1967, Ser. No. 5,926

Term of patent 14 years

(Cl. D26—13)

Fig. 1

Fig. 2

Fig. 3

Fig. 4

Fig. 5

Fig. 6

FIG. 1 is a perspective view of a control knob or simi-
lar article embodying my design.

FIG. 2 is a front elevational view thereof.

FIG. 3 is a back elevational view thereof.

FIG. 4 is a side view thereof.

FIG. 5 is a side view thereof, taken 90° from the view
of FIG. 4.

FIG. 6 is a sectional view taken on line 6—6 of FIG. 2.
I claim:

The ornamental design for a control knob or similar
article, substantially as shown.
